UNITED STATES PATENT OFFICE.

ROBERT H. ANTES, OF GENESEO, ILLINOIS.

AUTOMATIC DENTAL MALLET.

SPECIFICATION forming part of Letters Patent No. 242,853, dated June 14, 1881.

Application filed March 18, 1881. (Model.)

To all whom it may concern:

Be it known that I, ROBERT H. ANTES, of Geneseo, in the county of Henry and State of Illinois, have invented certain new and useful Improvements in an Automatic Dental Mallet; and I do hereby declare the following to be a full, clear, and exact description of the invention, that will enable others skilled in the art to which it appertains to construct and 10 make use of the same, reference being had to the accompanying drawings, and to letters of reference marked thereon, forming a part of this specification.

The object of this invention is to combine 15 with a dental instrument a malleting attachment adapted to have an automatic action; and it consists in the construction and arrangement of certain mechanism, as will be hereinafter more fully described in detail, and 20 set forth in the claims.

Figure 1 is a side elevation of a dental instrument embodying my improvement, showing the normal position of the mallet or hammer. Fig. 2 shows a vertical longitudinal section of the sliding sleeve and the position of 25 the mallet when in contact with the spindle or tool-holding shaft, and Fig. 3 a detached detail of construction.

Referring to the drawings, A represents a 30 sliding sleeve or hand-grasp, inclosing the vertical shaft or spindle A'; A², plugging-tool inserted in the shank end of the shaft A'; B, the mallet or hammer, and B' handle to the same.

35 The sleeve or hand-grasp A moves freely up or down on the shaft A', and is provided with the projecting lug a, to which the lower end of the connecting-rod B² is attached, the upper end of the connecting-rod being attached to 40 the horizontal lever C, as shown in the drawings. The inner end of the lever C is pivoted to the downward-projecting lug a', and the outer end is bifurcated, as shown in Fig. 3 of the drawings, so as to embrace the lower end 45 of the eccentric-lever C'. The lever C is provided with a number of perforations, a², for the adjustment of the upper end of the connecting-rod B², for the purpose of shortening or lengthening the stroke as may be required. 50 The central part of the eccentric-lever C' is pivoted to and has an oscillating bearing on

the outer bifurcated end of the arm C², is provided with the cam-projection a³, and the upper end terminating in the clip-extension a⁴, which incloses and holds the end of the mallet-handle. The inner end of the arm C² is perforated and slips on over the upper end of the shaft A', and is secured in position by means of the set-screw D. The inner end of the spring D' is inserted between the under side of the arm C² and the horizontal projection of the lug a', the parts being held in place by means of the screw D'. The loose end of the spring has a bearing on the under side of the cam a³, which, in connection with the eccentric-lever C', serves to return the mallet to its normal position after the delivery of each blow. This arrangement entirely dispenses with the necessity of employing an assistant to handle the mallet, and the operator is enabled to accurately regulate the force and rapidity of the blow as circumstances may require.

The mallet or hammer employed in connection with this device is provided with a handle composed of wood, which is used in preference to other material for the reason that it imparts to the hammer an elastic vibration or spring-like action, which has the effect of causing the hammer to deliver a more penetrating and packing blow than it would do were the handle composed of metal.

Having thus described my invention, what I claim, and desire to secure by Letters Patent, is—

1. In an automatic dental mallet, the combination, with the sliding sleeve A, of the connecting-rod B², the horizontal lever C, the projecting lug a', and the arm C², substantially as described.

2. In an automatic dental mallet, the eccentric-lever C', having the cam-projection a³ and the clip-extension a⁴ formed integral therewith, as shown and described.

3. In an automatic dental mallet, the combination, with the shaft A', of the arm C², the eccentric-lever C', pivoted to the outer bifurcated end of said arm, the handle B', and the mallet or hammer B, substantially as herein shown and described.

4. In an automatic dental mallet, the combination, with the arm C², of the mallet or

hammer B, the handle B', the eccentric vibrating lever C', the spring D', the lug a', and the horizontal lever C, substantially as herein shown and described.

5. In an automatic dental mallet, the combination of the following elements, consisting of the sleeve A, the shaft A', the connecting-rod B², the horizontal lever C, the eccentric-lever C', provided with the cam-projection a³

and the clip-extension a⁴, the spring D', the 10 arm C², the handle B', and the mallet or hammer B, all constructed and arranged to operate as herein shown and described.

ROBERT H. ANTES.
